UNITED STATES PATENT OFFICE.

WILLIAM HOOPER, OF TICONDEROGA, NEW YORK, ASSIGNOR TO HIMSELF
AND JOHN R. DE LAMAR, OF DENVER, COLORADO.

ORE-CONCENTRATOR.

SPECIFICATION forming part of Letters Patent No. 337,684, dated March 9, 1886.

Application filed August 31, 1885. Serial No. 175,813. (No model.)

To all whom it may concern:

Be it known that I, WILLIAM HOOPER, of Ticonderoga, in the county of Essex and State of New York, have invented certain new and 5 useful Improvements in Ore-Concentrators, of which the following is a full, clear, and exact description.

Reference is to be had to the accompanying drawings, forming part of this specification, in 10 which similar letters of reference indicate corresponding parts in both the figures.

Figure 1 is a sectional side elevation of one 15 of my improved ore-concentrators, parts being broken away. Fig. 2 is a sectional plan view of the same, parts being broken away.

The object of this invention is to provide ore-concentrators constructed in such a manner as to deliver the floating values, tailings, middlings, and concentrates into separate receivers, and which shall be reliable in operation and convenient in use.

The invention consists in the construction and combination of various parts of the ore-concentrator, as will be hereinafter fully described, and then pointed out in the claims.

A represents the frame of the machine, or of a building in which the machine is placed, and to which is journaled the upper end of the vertical shaft B. The lower end of the 20 vertical shaft B revolves in a step, C, attached to the floor of the building or to the frame of the machine.

Upon the lower part of the vertical shaft B is placed a sleeve, D, with the lower part of 25 which is rigidly connected the inner end of a bar, E.

To lugs attached to the outer end of the bar E is hinged one end of a connecting-bar, F, the other end of which is pivoted to a crank-pin secured to the crank-wheel G, so that the bar E will be vibrated by the revolution of the said crank-wheel G. The crank-wheel G is slotted radially to receive the crank-pin, so that the said crank-pin can be moved toward 40 or from the center of the said crank-wheel to give a less or greater throw to the crank. The crank-wheel G is attached to the inner end of a shaft, H, which revolves in bearings in posts I, or other supports attached to the floor of 45 the building, or to the frame of the machine.

To the outer part of the shaft H is attached a cone-pulley, J, to receive a belt, which also passes around a cone-pulley, K, attached to the shaft L. The shaft L revolves in hangers M, attached to the frame A, and is provided 55 with a fast pulley, N, and a loose pulley, O, to receive a driving-belt from any convenient power.

To the flanged upper end of the sleeve D are rigidly attached the inner ends of radial bars P, the outer ends of which are rigidly connected by bars Q.

Upon the middle parts of the radial bars P is placed an annular bar, R, which is connected with the said bars P by set-screws S, so that 65 the said annular bar R can be readily raised or lowered by operating the said set-screws S, to give a greater or a less inclination to the radial sluices T. The sluices T rest upon and are connected with the bars Q and R, and are 70 flared toward their outer ends, so as to form an annular series or table of sluices, which is vibrated from and by the vibrating bar E.

To the shaft B, above the series of radial bars P, is rigidly secured a collar, U, the lower 75 end of which is flanged, and to it are secured the inner ends of the radial feed-spouts V, by which the ore and water are conducted to the head ends of the sluices T, so that the said feed spouts will be carried around by and with 80 the shaft B.

To the flanged upper end of the collar U are rigidly attached the concentric feed-tubs W X, the outer one, W, of which is designed 85 to receive ore and water, and the inner one, X, is designed to receive water. The feed-tub W is provided with a discharge-tube, Y, through which the upper ends of the feed-spouts V are supplied with ore and water successively. The feed-tub X is provided with 90 a number of discharge-tubes, Z, through which the upper ends of the feed-spouts V, after the floating values have run off, are supplied with water to wash off, first, the tailings, then the middlings, and finally the concentrates. Ore 95 and water from any suitable reservoir are introduced into the feed-tub W through a spout, a, from any suitable reservoir. Water is introduced into the feed-tub X through a pipe, b, from any suitable reservoir.

To the flanged upper end of the collar U is rigidly attached the inner end of the bar e, the outer end of which, or a bar or strap attached to the said outer end, is bent downward 5 and inward, and is attached to the foot of the annular receiving-trough d. The receiving-trough d is attached to the outer ends of the radial bars e, the inner ends of which are rigidly attached to a flanged sleeve, f, placed 10 and revolving loosely upon the sleeve D, and resting on a shoulder of the said sleeve D, so that the receiving-trough d will be carried around by and with the vertical shaft B. The trough d is divided into four sections, g h i j, 15 by transverse partitions k, and each section is provided with discharge-openings l, from which pipes m lead to the concentric annular receivers n, surrounding the lower part of the vertical shaft B, and resting upon a supporting-frame, o. With this construction, when 20 the machine is operated and the ore and water enter the upper ends of sluices T, the floating values, being the lightest part of the material, will flow off into the section g of the trough d, 25 and will be conducted into its receiver n. The tailings, being the next lightest part, will be washed by the inflowing water into the section h, and will be conducted into its receiver n. The middlings, being the next lightest 30 part, will be washed into the section i, and the concentrates, being the heaviest part, will be washed into the section j, leaving the sluices T clean to receive a fresh supply of ore and water. This operation will be continuous, 35 the feed tubs W X and the receiving-trough d being carried around by the shaft B and moving at the same speed, so that the ore and water will be introduced into the upper ends of the sluices T in succession, while the said 40 sluices will be continuously vibrated by the crank-wheel G and its connecting and driving mechanism.

To the upper part of the vertical shaft B is attached a worm-wheel, p, into the teeth of 45 which meshes the worm q, attached to the shaft r. The shaft r revolves in hangers s, attached to the frame A, and to it is attached a fast pulley, t, and a loose pulley, u, to re-

ceive a driving belt from any convenient power.

Having thus described my invention, I claim as new and desire to secure by Letters Patent—

1. In an ore-concentrator, the combination, with the vertical shaft B, the annular series of inclined flaring sluices T, their supporting bars P, and sleeve D, of the rotating feed-tub W, attached to the said shaft B, and the series of radial spouts V, substantially as herein shown and described, whereby the ore and water are fed to the said sluices successively, 60 as set forth.

2. In an ore-concentrator, the combination, with the sluices T, spouts V, vertical shaft B, the sleeve D, placed upon the said shaft, the rotating feed-tub W, attached to the said shaft, 65 and the annular receiving-trough d, of the arm e, rigidly connected with the said feed-tub and receiving-trough, and the bars e and sleeve f, carrying the said feed-trough, substantially as herein shown and described, 70 whereby the said feed-tub and receiving-trough will be rotated to feed and receive the graded material from the sluices successively, as set forth.

3. In an ore-concentrator, the combination, with the vertical shaft B, the sleeve D, radial bars P, supported upon and directly attached to said sleeve, and the sluices T, of the arm E, the connecting-bar F, the crank-wheel G, and the horizontal shaft H, substantially as 80 herein shown and described, whereby the said sluices will be vibrated, as set forth.

4. The combination, with an annular series of horizontally-vibrating sluices, of a rotary trough at the outer ends of the said sluices, 85 partitions in said trough, a series of annular fixed receivers below the trough, corresponding in number to the divisions in said trough, and a pipe projecting from the under side of each division of the trough and extending to 90 a point over a receiver, substantially as set forth.

WILLIAM HOOPER.
